UNITED STATES PATENT OFFICE.

LOUIS HANSON, OF RACINE, WISCONSIN, ASSIGNOR TO OTTO E. BARNETT, OF CHICAGO, ILLINOIS.

RAIL-STAY.

1,130,815.

Specification of Letters Patent.

Patented Mar. 9, 1915.

Application filed May 22, 1913. Serial No. 769,238.

To all whom it may concern:

Be it known that I, LOUIS HANSON, a citizen of the United States, residing at Racine, in the county of Racine and State of Wisconsin, have invented certain new and useful Improvements in Rail-Stays, of which the following is a specification.

My invention relates to railway track devices known as rail stays, rail anchors, or 10 anti-creepers, the purpose of which is to prevent the longitudinal creep of railway rails under the stresses exerted by the passage of trains over the rails.

The primary object of the invention is to 15 provide, in a device of this sort, effective means for preventing a loosening or retrograde movement as between the parts which operate to grip or clamp the rail, so as thereby to insure at all times and under all conditions the proper and intended operation of the device.

The hold of rail stays on the rails becomes 20 loosened from a variety of causes, the chief of which are the vibration to which the rail is subjected by the passage of the train thereover, contraction and expansion of the metal of the rail and stay due to temperature changes, and the reaction or reverse longitudinal movement which, it is believed, 25 takes place as soon as the train has passed by and the forward stresses cease. Although various expedients have been tried for preventing this tendency of the parts to become loose or back away one from the other, such, 30 for example, as the use of nut locks on anti-creepers of the bolt type and rack and tooth arrangements on devices of the wedge type, 35 none of these expedients have proven altogether successful when put to the test of actual service.

My invention overcomes this difficulty and solves the problem in a very satisfactory manner by interposing between the rail and some portion of the anti-creepers, or between 45 the relatively movable parts of the anti-creepers itself, a soft compression and friction pad or insert of material such as wood, fiber, vulcanite, soft metal, or the like, which is more resilient or adhesive, or preferably, 50 both more resilient and adhesive than the metals of which the rail and anti-creepers are composed, which element, besides absorbing vibration, takes a better frictional grip on the metal surfaces or surfaces against which 55 it bears than is possible where the parts in

contact are both relatively hard metal such as steel or malleable iron. It will be obvious that this expedient might be employed in a number of different ways upon variously constructed anti-creepers. I have shown it as applied to several common types of anti-creepers. I do not wish, however, to be understood as limiting the applicability of the invention to these particular devices.

With reference to the drawing, Figure 1 is a view, in perspective, of a section of rail showing applied thereto an anti-creepers constructed in accordance with my invention, and also one of the cross ties on which the rail is supported. Fig. 2 is a sectional plan of the parts shown in Fig. 1. Fig. 3, is a view, in perspective, of the key or wedge of the device fitted with a pad of soft material. Fig. 4 is a plan view illustrating another form of rail stay with the device of my invention applied thereto. Fig. 5, is a sectional view taken on line 5—5 of Fig. 4. Fig. 6, is a view, in perspective, of the wedge forming a part of this rail stay. Fig. 7, is a cross-sectional view of the wedge and insert. Fig. 8, is a plan view of another type of stay in which the soft, compressible pad or insert is somewhat differently applied. Fig. 9 is a sectional view taken on line 9—9 of Fig. 8. Figs. 10 and 11, are views in perspective of the two elements constituting the rail stay shown in Figs. 8 and 9. Fig. 12 is a sectional view of a bolt type of rail stay utilizing the device of my invention; and Fig. 13, is a view in perspective of one of the jaw elements of this stay.

Like characters of reference designate like parts in the several figures of the drawing.

Referring first to Figs. 1 to 3, inclusive, A designates a railroad rail and B one of the cross ties on which it is supported. The rail stay shown for the purpose of illustrating the improvement constituting my invention consists of a malleable iron casting 25 provided at one end with a jaw 26 which engages one of the base flanges of the rail, and at the other end, a larger jaw 27 between which and the rail is driven a key or wedge 28, the latter being preferably 105 formed with a groove 29 into which the edge of the rail base is received. The casting 25 is formed with a tie-abutting member 30. This part of the device is described and claimed as a "tie-abutting member" but it 110

might of course be arranged against any other fixed element or part of the roadbed, and I do not wish to be understood as excluding such other arrangements in so describing and claiming this part of the device. In devices of this type difficulty has always been experienced in keeping the wedge from backing out of its operative position. The constant vibration of the rail 10 operates upon the wedge to loosen it from the jaw into which it is driven. The expansion and contraction of the metal parts due to temperature changes may have the same result. When the co-engaging surfaces of the key and of the jaw are both 15 metal and relatively smooth, it does not require a great deal of vibration to start the wedge backing out of place. To overcome this I fit into the back edge of the wedge 20 an insert 31 of some relatively soft, compressible material such as wood, fiber, soft metal, or the like. This insert, as a matter of convenience in shipping, is fastened to the key in some suitable manner. For example, I have shown one end of the groove 25 32 in which the pad is set undercut as at 33. A lug 34 on the back of the key at the other end of the groove is hammered down on the insert so as to hold the same in position. 30 When the wedge 28 is driven in between the jaw 27 and the base of the rail the insert or pad absorbs a good deal of the vibration to which the device is subjected and to a certain extent by its resiliency compensates for looseness due to differences in contraction and expansion between the rail and the rail stay and thereby materially decreases the forces tending to loosen the wedge. Moreover, the friction between the 35 40 insert and the inner surface of the jaw 27 is considerably greater than the friction between two similarly shaped surfaces both of metal, and this circumstance further checks the tendency of the wedge to become loose. 45 In Figs. 4 to 7, inclusive, the insert is applied to the same type of rail stay in a somewhat different manner from that shown in the preceding figures. The key or wedge 35 corresponding to the wedge 28 in Figs. 50 1 to 3, inclusive, has a wedge-shaped opening cut through the back of the same, into which is fitted a soft, adhesive insert 36 of wood or the like, one edge 37 of which bears against the inner surface of the jaw 27, the 55 opposite edge 38 bearing against the base flange of the rail. This arrangement minimizes slip both between the wedge and the other casting of the stay and between the wedge and the rail. In the other jaw 26 a 60 insert 36 of wood, or the like, may be arranged so as to bear against the edge of the rail base on this side of the rail.

The rail stay shown in Figs. 8 to 11, inclusive, consists of two jaw castings 39 and 40 which have a wedging engagement one

with the other under the base of the rail, the casting 39 being formed with a tapered groove 41 and the casting 40 with a tongue 42 which slides in this groove. One of the castings, for example the casting 39, is provided with a tie-abutting member 43. The hold of the device on the rail depends entirely upon the frictional grip which the jaw members 39 and 40 take upon the base of the rail. This frictional grip is very materially increased and the danger of the same being loosened by vibration diminished by providing one or each of the castings with a compressible, relatively adhesive pad or insert. In the drawings I have shown the casting 39 provided with an insert 44 of this character and the casting 40 with a similar insert 45. As shown, these inserts are arranged under the base flange of the rail. 75 80 85

In Fig. 12 I have shown the same expedient as employed in connection with the bolt type of rail stay. The device is made up of two jaw members 46, 47 held together by a bolt 48 and nut 49. Either of said members may be provided at any suitable place with a pad of relatively soft adhesive material to increase the frictional grip of the device upon the rail and absorb vibration, or, if need be, both jaw members 95 may be so constructed. I have shown each jaw member furnished with a soft, compressible insert 50, the edges of which are grooved so that it is held in place by ribs 51 formed on the casting. 90 100

I claim:

1. In a rail stay, the combination with a tie abutting member, of rail gripping means comprising two co-engaging elements, and a body of relatively soft material interposed between said elements so as to absorb vibration. 105
2. In a rail stay, the combination with a tie abutting member, of rail gripping means comprising elements one of which is movable with respect to the other to produce a grip of the device upon the rail, and a body of relatively soft material interposed between said elements. 110
3. In a rail stay, the combination with a tie abutting member, of rail gripping means comprising a wedge, a jaw between which and the rail said wedge is adapted to be driven, and a body of relatively soft material between the wedge and the opposed surface of said jaw. 115 120
4. In a rail stay, the combination with a tie abutting member, of rail gripping means comprising a wedge, a jaw between which and the rail said wedge is adapted to be driven, the back edge of said wedge being formed with a recess and a body of relatively soft material fitted into said recess. 125
5. In a rail stay, the combination with metal rail gripping members adapted to en- 130

gage opposite edges of the base flange of a rail, one of said members being provided with a tie abutting flange, of a body of material softer and more adhesive than the metal of said rail and rail gripping means arranged in wedging position between one of said members and the rail.

6. In a rail stay, the combination with rail gripping means comprising members adapted to be held in frictional engagement with the rail, one of which is provided with a tie abutting flange, of a body of material softer and more adhesive than the metal of said rail and rail gripping means interposed in wedging position between the rail and one of said members so as to be in frictional engagement with the rail.

7. The combination with a rail stay comprising metallic means adapted to be held in operative frictional engagement with the rail, and means adapted to anchor said device so as to prevent movement of the rail in a given direction, of a non-metallic insert interposed between said metallic means and the rail so as to be held in wedging frictional engagement with the rail.

8. The combination with an anti-creeping device comprising metal rail engaging jaws adapted to engage the opposite edges of the base of a rail and a tie-abutting member, of a body of material softer and more adhesive than the metals of said jaws and rail interposed between one of said jaws and the rail so as to be held in frictional engagement with the rail.

9. The combination with a rail stay comprising a pair of jaws adapted to fit over a rail base, a tie-abutting member, a wedge adapted to be interposed between one of said jaws and a portion of a railway rail so as to hold said device in gripping engagement with

said rail, and a non-metallic member extending through said wedge so that one side thereof will engage the rail and the other side thereof will engage one of said jaws. 45

10. The combination with a rail stay comprising metal rail gripping means and a tie-abutting member, of a body of material softer and more adhesive than the metals of which said rail and rail gripping means are composed arranged in wedging position at one edge of the base flange of the rail so as to increase the effectiveness of the engagement of said rail gripping means upon the rail. 50

11. The combination with a rail stay comprising gripping means and a tie-abutting member, of a non-metallic insert arranged in wedging position at one edge of the base flange of the rail so as to increase the effectiveness of the engagement of said rail gripping means upon the rail. 55

12. The combination with a rail stay comprising metal rail gripping means and a tie-abutting member, of a wooden insert the grain of which runs transversely of the rail, which is arranged so as to increase the effectiveness of the engagement of said rail gripping means with said rail. 60

13. An anti creeping device comprising oppositely disposed jaws adapted to produce a grip on opposite edges of the base of a rail, a tie-abutting member, and a body of material softer and more adhesive than the metals of said jaws and rail interposed between one of said jaws and the rail so as to be held in frictional engagement with the rail. 70
